MACHINE FOR FORMING U SHAPED SHACKLES

John Wycliffe Leighton, Port Huron, Mich.

Application November 30, 1932
Serial No. 644,985

9 Claims. (Cl. 29—34)

The principal objects of this invention are to facilitate the manufacture of single piece U-shaped shackles, whereby the cost of production will be reduced to the minimum and a uniform structure produced, and to devise a machine of simple and durable construction.

The principal feature of the invention consists in the novel construction and arrangement of a pair of relatively moveable die members and a pair of rollers, whereby on the movement of the rollers over the die members, a metal bar is compressed and deformed, and the ends of the bar projecting from the compressing portion are engaged by roller dies to bend the bar in the plane of the deformed portion over an anvil arranged between the moveable dies.

In the drawings, Figure 1 is a vertical sectional elevational view of the press for forming the U bolt.

20 Figure 2 is a vertical sectional view of the press taken at right angles to the section shown in Figure 1.

Figure 3 is a plan view of the die press. Figure 4 is an elevational view of the U bolt.

25 Figure 5 is a sectional elevational view of the U bolt taken at right angles to Figure 4.

In the manufacture of a U-shaped shackle such as illustrated in Figures 4 and 5, it is important that great accuracy be obtained in producing the shackles of uniform dimensions, both as to shape, 30 length of the arms, deformation of the central portion and the bending to produce the parallel ends with their axes in alignment with the median plane of the flattened portion A of the shackle.

In the construction of the machine as herein shown, the dies are placed on a double action press and the outer ram 1 is provided with recessed blocks 2 adjustably mounted therein and secured in their adjusted positions by the adjusting screws 3.

40 The recesses 4 in the blocks 2 are open at the top to receive straight steel bars and the ends of such bars abut the ends of the recesses 4 to accurately position the bars and definitely limit elongation thereof.

The inner ram 5 operates at the same rate of speed as the outer ram during the initial operation and said inner ram has a centrally arranged die block 6, the bottom of which is shaped to conform to the inner shape of the finished U bolt and is grooved vertically to ultimately receive the parallel ends of the bolts.

45 Hinged at either side, of the centre die block 6 are a pair of blocks 7, which at the bottom

ends are provided with inwardly extending elliptical-shaped projections 8 conforming to the shape of the depressions 9 in the sides of the looped portion of the U bolt.

Spiral compression springs 10 housed in recesses in the centre block 6 hold the hinged blocks 7 outwardly to an outward limit position so that the projections 8 will pass to either side of the heated rod held between the blocks 2 in the outer ram.

45 Mounted in the base 11 are a pair of cylindrical rollers 12, the perimeters of which are spaced apart to engage the outer flat faces of the pivotal die blocks 7 and as the inner ram moves downwardly, said rollers force the die blocks 7 70 inwardly toward each other, so that the elliptical projections 8 thereof are pressed into and deform the central part of the heated length of rod held between the blocks 2.

During this operation the cams operating the rams of the press operate said rams at a uniform speed and the positioning blocks 2 hold the heated rods centrally to receive the impression of the dies 8 and also prevent the elongation of the bar when the bar is undergoing the flattened 80 operation.

The inner ram then travels ahead of the outer ram and while the rollers 12 hold the die blocks 7 in their inward position gripping the heated and partially deformed bar. The dies move between a pair of grooved rollers 14 which are arranged in alignment with the centre line of the blocks 2 and the further downward movement of the centre ram passing between the grooved rollers affects the upward bending of both ends 90 of the bar simultaneously, thus forming the U-shaped shackle members as illustrated in Figure 4.

The outward sides of the die blocks 7 are provided with parallel surfaces 15 to retain engagement with the peripheries of the rollers 12 until the ends of the shackle have been bent upwardly and from the points 15' the blocks are cut away so that the action of the springs 10 forces them outwardly so that the die portions 8 are moved 100 clear of the bolt.

A pair of pivotal dogs 16 mounted below the grooved rollers 14 are spring held inwardly toward each other by the spring bolts 17. The dogs 16 spread apart as the U bolt passes downwardly between the grooved rollers 14 and immediately the ends of the U bolt pass the said dogs they spring inwardly, so that upon the return movement of the ram, the dogs engage the upper ends of the U bolt and strip the same from 110

the centre die allowing it to drop through the opening 18.

In the operation of this machine the heated rod is inserted between the die blocks 2 with the ends extending into the recesses 4. The inner ram 5 moves downwardly until the centre die block 6 engages the rod and the rams 1 and 5 then move downwardly in unison. The blocks 7 carried by the centre ram engage the rollers 12 and are pressed inwardly thereby forcing the projections 8 into the heated metal bar and deforming the centre thereof.

The continued movement of the dies brings the heated metal bar into contact with the grooved rollers 14 which bend the end portions upwardly to form the U-shaped member. The dies 8 are released by the passage of the parallel faces of the members 7 past the pressure rollers 12 and the formed shackle is stripped from the centre block by the strippers 16.

The device is of simple and rugged construction, is easily operated and produces, in a single operation, a shackle of uniform dimensions prepared ready for threading.

25 What I claim as my invention is:—

1. A machine for forming shackles comprising, means for positively gripping and concurrently flattening a bar of metal midway of its length, and means for simultaneously bending the ends of said metal bar in the same plane as the flattened portion and at right angles to the central portion thereof while the latter is positively gripped by said first-mentioned means.

2. A machine for making shackles comprising, means for bending the ends of a bar of metal to form a U-shape, and gripper means for compressing and deforming said bar midway of its length in a direction and form to maintain the ends in their parallel relation, said gripper means acting to positively retain said bar against longitudinal shifting during the bending operation.

3. A machine for forming U-shaped shackle bolts comprising, an anvil member, die members adapted to engage a bar of metal midway of its length, means adapted to force said die members to deform the central portion of said bar, and means for engaging and bending said bar into a U-shape while its central portion is rigidly held, the bending being done in the direction at right angles to the direction of movement of said die member.

4. A machine for forming U-shaped shackle bolts comprising, a reciprocable member, means carried by said reciprocable member adapted to engage and grip a bar of metal midway of its length, means adapted to force said latter means carried by the reciprocable member into deforming contact with the central portion of said bar, and grooved rollers rigidly held in a position to engage the ends of said metal bar and bend same simultaneously to a position at right angles to the centre portion and in alignment with the plane of the central portion during the movement of said reciprocating member.

5. A machine for forming U-shaped shackle bolts comprising, an anvil member having longitudinal grooves therein, a pair of die blocks hav-

ing die portions adapted to engage and deform the metal bar placed therebetween, a pair of rollers mounted to engage said die blocks and to press them against said metal bar, a pair of grooved rollers arranged in alignment with the grooved sides of said anvil adapted to engage the metal bar projecting beyond the anvil and to bend same into said longitudinal grooves, and means for stripping the formed U-bolt from the anvil member following the forming of the bolt.

6. A machine for forming U-shaped shackle bolts comprising, a reciprocable anvil member having longitudinal grooves in opposite sides, a pair of die blocks pivotally secured at their upper ends on opposite sides of said anvil member and having die portions extending beneath the end of said anvil member, the outer sides of said blocks having flat parallel faces at the free ends and recessed portions between said parallel faces and the pivot ends, a pair of rollers mounted to engage the flat parallel faces of said blocks as the anvil moves longitudinally to press the die portions into the metal bar placed between same, means adapted to force said die blocks outwardly to free the metal bar as the rollers engage the recessed faces, means for bending the ends of said bars into the longitudinal grooves of the anvil while the bar is gripped by said die blocks, and means for stripping the formed shackle from the anvil.

7. A machine for making shackle bolts comprising means for compressing and deforming a bar of metal midway of its length, means engaging the ends of said bar during the deforming of the central portion to limit elongation of the bar, and means for bending the ends of said bar to form a U-bolt.

8. A machine for forming U-shaped shackle bolts comprising a reciprocable member, means carried by said reciprocable member adapted to engage a bar of metal midway of its length, adjustable means adapted to force said means carried by the reciprocable member into pressure contact with said metal bar to deform the said central portion, and adjustable means for engaging and bending the ends of said bar to form parallel ends while the centre portion is rigidly held.

9. A machine for forming U-shaped shackle bolts comprising, a die block having a central opening, a pair of rollers adjustably mounted on parallel axes one at each side of said opening, a pair of grooved rollers adjustably mounted on parallel axes one at each of the other sides of said opening, a reciprocating anvil member adapted to pass between said pairs of rollers a pair of die blocks mounted on opposite sides of said anvil member and adapted to engage one set of said rollers and having dies adapted to engage and compress a metal bar placed therebetween and hold said bar rigidly to the anvil member while the ends of said bar engage the other pair of rollers, and stripping members mounted below the second set of rollers adapted to engage the ends of the bolt and strip it from the anvil on its reverse movement.

JOHN WYCLIFFE LEIGHTON.
